UNITED STATES PATENT OFFICE

COLIN GRANT, OF JACKSON, MICHIGAN, ASSIGNOR OF ONE-THIRD TO CLARE R. DEEM
AND ONE-THIRD TO SAMUEL GAY, BOTH OF JACKSON, MICHIGAN

DETACHABLE HANDLE

Application filed May 26, 1930. Serial No. 455,646.

The objects of the invention are:

First, to provide a detachable handle for a traveling bag or luggage.

Second, to provide such a handle which has a minimum of fastening devices.

Third, to provide a handle for luggage which is very superior owing to the absence of stitches, a smooth, soft, firm handle being secured.

10 Further objects and objects pertaining to details and economies will appear from the detailed description to follow.

A preferred embodiment of my invention is illustrated in the accompanying drawings, 15 in which:

Fig. 1 is a perspective view of such a handle substantially full size attached to the D's or rings of a traveling bag.

Fig. 2 is a detail plan view of the structure, somewhat reduced, portions of the connecting strap being cut away and the inner end of the connecting strap detached to show details of construction.

Fig. 3 is an enlarged detail longitudinal 25 sectional view through one end up to the central portion of the handle taken on a plane corresponding to that indicated by line 3—3 of Figs. 1, 2 and 4.

Fig. 4 is an enlarged detail central cross 30 sectional view taken on line 4—4 of Figs. 1, 2 and 3.

Fig. 5 is an enlarged detail perspective 35 view of the under side of one end of the handle showing the method of inserting the connecting strap into the D.

The parts will be identified by their numerals of reference which are the same in all the views.

1 is the main body piece of the handle 40 made of a heavy piece of leather, bowed and convex on its under side and with a longitudinal channel extending from end to end on the top side, the structure being slightly tapered at the end and the cross 45 sectional form clearly appearing in Fig. 4.

2 is a soft piece of leather covering 50 wrapped around this body part, finished and soft on the surface, making it pleasant to the feel of the hand. The edges of the covering meet on a mid longitudinal line

in the bottom of the channel on the top of the handle. These parts are molded and pressed very effectively together.

A transverse slot 3 is cut in each end of this covered handle part and an elongated connecting strap 4 is disposed in the channel with projecting ends, the same being tapered towards the ends, as clearly indicated where the ends appear in Figs. 2 and 5. In the channel at each end of the 55 body portion are disposed small blocks of leather 5 which fill the channel about half way to the top. The connecting strap 4 is then disposed in the channel and the same is riveted at each end to the body of the 60 handle by the rivet 6 through these filler blocks. The same may be secured in any other way, but rivets are preferred on account of their simplicity. The handle is 65 very effective without the rivets, when the 70 parts are effectively molded and the ends of the connecting strap 4 are threaded up through the slots 3 as indicated. The rivets hold the structure always in assembled 75 shape, ready for attachment, but are not a necessity.

In the ends of the connecting strap 4 are formed slotted holes 7. These ends are of such length that they substantially meet at the middle of the handle when inserted back 80 through the slots. The ends of the connecting strap are inserted down through D's 8 and then inserted up through the slots 3. Their meeting ends are then secured together at the center of the handle in the bottom of the channel formed therein, underneath the central portion of the connecting strap 4.

This is accomplished by a connector 9. 90 This is formed with oppositely directed downwardly projecting heads 10 which are secured to the main body by necks 11. The heads are inserted downwardly through the meeting ends of the connecting strap 95 through the slotted holes 7. The pull on the D's or rings puts tension on the connecting strap and draws the same securely to the bottom of the channel where it is effectively covered and concealed by the 100

loosely overlying central portion of the said connecting strap 4.

Thus a handle without stitching is effectively produced with the mere use of a pair 5 of rivets. Stitchings might be inserted for ornamentation, but they are wholly unnecessary.

Of course the handle would be effective without providing the soft leather covering 10 for it, but the means provided effectively retain the same in place without any stitching, making a perfectly smooth, finished handle of great strength and comfortable 15 for the handling of traveling bags and luggage.

The handle as shown can be very readily attached and detached. If the ends of the connecting strap are permanently secured together, a highly desirable handle is produced.

I desire to state that the structure may be greatly modified without departing from my invention. I desire to claim the same 20 in its specific form as detachable, and I also 25 desire to claim the same broadly as pointed out in the appended claims.

Having thus described my invention what I claim as new and desire to secure by Letters Patent is:

30 1. In a detachable handle, the combination of a main body portion of leather formed into channel shape and tapered toward the ends, a soft leather covering embracing the body portion, the whole being 35 perforated with a transverse slot near each end, a leather block in the channel near each end of the handle, a connecting strap disposed in the said channel extending around the ends and upwardly through the said slots 40 and meeting and joined at the center, a detachable connector at the center for joining the ends of said connecting strap comprising a body portion with outwardly projecting heads connected by necks, and rivets 45 through the said connecting strap and body portion at each end of the handle.

2. In a detachable handle, the combination of a main body portion of leather formed into channel shape and tapered toward the ends, a soft leather covering embracing the body portion, the whole being 50 perforated with a transverse slot near each end, a leather block in the channel near each end of the handle, a connecting strap disposed in the said channel extending around the ends and upwardly through the said slots and meeting and joined at the center, and a detachable connector at the center for joining the ends of said connecting strap comprising a body portion with outwardly projecting heads 55 connected by necks, the said connecting strap and body portion being joined at the ends of the handle.

3. In a detachable handle, the combination of a main body portion of leather

formed into channel shape and tapered toward the ends and perforated with a transverse slot near each end, a leather block in the channel near each end of the handle, a connecting strap disposed in the said channel extending around the ends and upwardly through the said slots and meeting and joined at the center, and a detachable connector at the center for joining the ends of said connecting strap comprising a body portion with outwardly projecting heads connected by necks, the said connecting strap and body portion being joined at the ends of the handle.

4. In a detachable handle, the combination of a main body portion of leather formed into channel shape and tapered toward the ends, and perforated with a transverse slot near each end, a leather block in the channel near each end of the handle, and a connecting strap disposed in the said channel extending around the ends and upwardly through the said slots and meeting and joined at the center, the said connecting strap and body portion being joined at the ends of the handle.

5. In a detachable handle, the combination of a main body portion of leather formed into channel shape and tapered toward the ends, a soft leather covering embracing the body portion, the whole being 95 perforated with a transverse slot near each end, a connecting strap disposed in the said channel extending around the ends and upwardly through the said slots and meeting 100 and joined at the center, a detachable connector at the center for joining the ends of said connecting strap comprising a body portion with outwardly projecting heads connected by necks, and rivets through the 105 said connecting strap and body portion at each end of the handle.

6. In a detachable handle, the combination of a main body portion of leather formed into channel shape and tapered toward the ends, a soft leather covering embracing the body portion, the whole being 110 perforated with a transverse slot near each end, a connecting strap disposed in the said channel extending around the ends and upwardly through the said slots and meeting and joined at the center, a detachable connector at the center for joining the ends of said connecting strap comprising a body portion with outwardly projecting heads 115 connected by necks, the said connecting strap and body portion being joined at the ends of the handle.

7. In a detachable handle, the combination of a main body portion of leather formed into channel shape and tapered toward the ends, and perforated with a transverse slot near each end, a connecting strap disposed in the said channel extending around the ends and upwardly through the 120

said slots and meeting and joined at the center, a detachable connector at the center for joining the ends of said connecting strap comprising a body portion with outwardly 5 projecting heads connected by necks, the said connecting strap and body portion being joined at the ends of the handle.

8. In a detachable handle, the combination of a main body portion of leather 10 formed into channel shape and tapered toward the ends, and perforated with a transverse slot near each end, and a connecting strap disposed in the said channel extending around the ends and upwardly through 15 the said slots and meeting and joined at the center, the said connecting strap and body portion being joined at the ends of the handle.

9. In a detachable handle, the combination of a main body portion of leather 20 formed into channel shape and tapered toward the ends, and perforated with a transverse slot near each end, a leather block in the channel near each end of the handle, and 25 a connecting strap disposed in the said channel extending around the ends and upwardly through the said slots and meeting and joined at the center.

10. In a detachable handle, the combination of a main body portion of leather 30 formed into channel shape and tapered toward the ends, and perforated with a transverse slot near each end, and a connecting strap disposed in the said channel extending 35 around the ends and upwardly through the said slots and meeting and joined at the center.

In witness whereof I have hereunto set my hand.
